UNITED STATES PATENT OFFICE.

LEEDHAM BINNS, OF PATERSON, NEW JERSEY, ASSIGNOR OF ONE-HALF
TO WILLIAM T. RYLE, OF SAME PLACE.

FLIER FOR SPINNING-MACHINES.

SPECIFICATION forming part of Letters Patent No. 295,974, dated April 1, 1884.

Application filed April 17, 1883. (No model.)

To all whom it may concern:

Be it known that I, LEEDHAM BINNS, of Paterson, in the county of Passaic and State of New Jersey, have invented certain new and 5 useful Improvements in Fliers for Spinning-Machines, of which the following is a full, clear, and exact description.

The object of my invention is to overcome the difficulty now experienced of the eye of 10 the flier becoming notched by the wearing of the thread; and to this end my invention consists of means for causing the thread to have a lateral traverse along the leg or arm of the flier, so that it will not have a single contact- 15 point with the flier, as heretofore.

The invention also consists of a flier folded back upon itself to form a loop to act in conjunction with an eccentric plate for producing the lateral traverse of the thread, and also 20 of the special arrangement of the flier and eccentric plate, all as hereinafter described and claimed.

Reference is to be had to the accompanying drawings, forming a part of this specification, 25 in which similar letters of reference indicate corresponding parts in both the figures.

Figure 1 is an elevation of a spindle and 30 a bobbin having my new and improved flier applied thereto in section. Fig. 2 is a plan view of the flier.

In carrying my invention into effect I prefer to employ the metal eccentric plate *a*, which has formed or secured upon it the hollow sleeve *b*, that fits tightly or loosely upon the spindle *c* above the bobbin *d*; or, instead of this hollow sleeve, the eccentric might be placed loosely upon the bobbin, in which case the sleeve *b* should be flanged at the bottom the same as at the top, and should fit tightly upon the 35 spindle to prevent the eccentric plate from coming off from the spindle when in operation; or the eccentric plate might be attached to or formed upon the upper end of the bobbin. Upon the sleeve *b* is placed loosely the button *f*, that carries the arms *e* of the flier. These arms are made of wire, and are folded back at their outer ends to form the elongated 40 loops *g*, through which the thread or threads *h*, coming from the bobbin *d*, pass. The sleeve 45 *b* is, by preference, flanged at its upper end, as shown at *i*, for holding the button on the

sleeve, thus uniting the flier and eccentric plate *a*; and *i* is a separate button placed upon the upper end of the spindle *c*, to prevent all danger of the plate *a* and flier coming off from 55 the spindle while in motion.

In operation, in spinning or doubling yarn or throwing silk, the thread or threads pass from the bobbin over the edge of the eccentric plate *a*, thence up through the elongated 60 loop *g* of the arm *e* to the horizontal bobbin in front of the arms *e* of the flier. The plate *a*, being eccentric and revolving with the spindle, causes the thread or threads to have a 65 sidewise movement or traverse to the extent of the eccentricity of the plate *a*, which constantly changes the contact-surface of the thread with the flier-arm, thus effectually preventing the thread from wearing a notch in the flier, and this is of great advantage, since 70 it avoids the danger of the thread becoming broken and damaged by the notch, and greatly increases the durability of the flier-arm, thus avoiding delay for repairs and expense for new flier-arms, and at the same time enables a 75 greater speed to be attained than by the common flier. Besides, the attachment is cheap and convenient, and is adapted for spinning or doubling all kinds of yarn and silk.

Having thus described my invention, I claim 80 as new and desire to secure by Letters Patent—

1. The combination, with a flier, of an eccentric plate for causing the thread to have a traversing movement, substantially as and for the purposes set forth. 85

2. The eccentric plate *a*, in combination with the loose button *f*, provided with the flier-arms *e*, substantially as set forth.

3. The flier-arms *e*, having the elongated loops *g*, in combination with means, substantially as described, for changing the point of contact of the thread with the flier, substantially as and for the purposes set forth. 90

4. The eccentric plate *a*, having the hollow sleeve *b*, in combination with the flier-button *f*, held loosely upon the sleeve, substantially 95 as and for the purposes set forth.

LEEDHAM BINNS.
